UNITED STATES PATENT OFFICE

2,630,190

FILTER BAG FOR SUCTION CLEANERS

Belle Cordray, Canton, Ohio, assignor to The Hoover Company, North Canton, Ohio, a corporation of Ohio

Application January 5, 1951, Serial No. 204,617

2 Claims. (Cl. 183—51)

1

This invention relates to a dirt filtering bag for suction cleaners and more particularly to a simplified structure and method of making the bag.

Filter bags at present embodied in tank type suction cleaners are formed from two pieces of material, one for the cylindrical wall and the other for the closed end wall. It has been the practice to first sew the longitudinal edges forming the cylindrical side wall and thereafter stitch the end wall to one edge of the annular side wall. The second sewing operation requires constant rotation of the end wall and the cylindrical wall with respect to the needle station in order to form the annular seam. During this operation the operator can stitch only a small portion of the annular seam and the sewing machine must be stopped and started several times to adjust the material for each short stitching operation before completing the annular seam between the end wall and side wall of the bag.

It is therefore an object of the invention to provide a filter bag to reduce the sewing time and also the handling between successive stitching operations. Another object is to provide a filter bag by sewing the side wall material to the end wall material and thereafter stitching the side wall into cylindrical form. A further object is to provide a filter bag by so cutting the end wall that the blanks forming the bag are more easily manipulated with respect to the needle station during the sewing operation. A further object is to provide a filter bag by cutting a radial slit in the end wall material to permit the sewing of one end of the side wall material to the end wall in substantially one continuous stitching operation, and thereafter securing the slit and longitudinal edges of the side wall together in substantially one stitching operation. Another object is to provide an improved filter bag for suction cleaners. Other objects and advantages of the invention will be apparent from the following description and drawings, wherein

Figure 1 is a side elevation partly in section of a tank type cleaner having the improved filter bag;

Figure 2 is a plan view of the two pieces of material from which the bag is made;

Figure 3 is a plan view of the material forming the bag end wall provided with a radial cut prior to sewing;

Figure 4 is a perspective view of the stitching operation attaching the side wall material to the end wall material; and

Figure 5 is a perspective view of the completed filter bag.

Figure 1 discloses a filter bag 10 embodied in a tank type cleaner comprising an elongated casing 11 closed at its exhaust end by a cap 12 having a port 13, and its inlet end is closed by a re-

2

movable cap 14 having a port 15, and the cap 14 is attached to the casing 11 by a latch 16. The ports 13 and 15 are adapted to receive one end of a hose provided at its opposite end with a suitable surface cleaning tool. The casing is supported on a pair of skids 17 and is provided with a carrying handle 18. Within the casing 11 is a motor-fan unit 19 supported at its opposite ends by frames 20 and 21, both of which are provided with openings 22 for passage of air. The dirt filtering bag 10 is provided at its open end 23 with an expandable wire frame 24 for attachment to a bag ring 25 removably held in position by the front end cap 14. In operation of the cleaner, the bag 10 filters the dirt from the dirt laden air stream entering the opening 15 and the cleaned air is then discharged through the outlet 13.

The filter bag 10 is made from two blanks 30 and 31 of suitable cloth or other dirt filtering fabric, the blank 30 forming the closed end wall and the blank 31 providing the cylindrical side wall. The blank 30 has a peripheral edge 35 substantially equal to the girth of the bag 10, and the blank 31 has opposite ends 36 and 37 of a length equal to the peripheral edge 35, and the longitudinal edges 38 and 39 are substantially the length of the completed bag 10.

The first step in constructing the bag 10 is to cut the blank 30 as indicated at 40 in a radial direction to a point short of the center 41 to provide cut edges 42 and 43.

The two blanks are then placed in a sewing machine with the cut edge 42 in line with the longitudinal edge 38 and the peripheral edge 35 is then stitched to the end 36 of the blank 31 to form a seam 44. At the end of this sewing operation, the cut edge 43 will be aligned with the longitudinal edge 39 of the blank 31. During this sewing operation, the cut edges 42 and 43 are spread apart to assist the operator in adjusting the arcuate edge 35 of the blank 30 with the straight edge 36 of the blank 31. In addition, the cut 40 permits the cut edges 42 and 43 to be spread apart and prevents the blank 31 from forming a complete cylindrical wall as the seam 44 is being completed near the cut edge 43, and thus does not interfere with the operator's line of vision in stitching the last portion of the seam 44. The cut edges 42 and 43 also permit the end wall material to be spread apart so that the operator can easily arrange and line up the blanks 30 and 31 as the seam 44 is being stitched and thus reduces handling and interruptions in adjusting of the material during the sewing operation.

The next step comprises overlapping the longitudinal edges 38 and 39 of the side wall material and placing the free end 37 under the needle to stitch a seam 46 in a straight line without interruption during the sewing operation. When stitching of the seam 46 approaches the cut

edges 42 and 43 in the end wall 30, the operator laps the edges 42 and 43 and arranges the latter in a straight line with the sewed portion of the seam 46 to stitch an end wall seam 47 in a substantially straight line sewing operation with the side wall seam 46. If desired, an overcasting stitch may be provided at 49 and 50 to prevent raveling of the exposed edges.

The bag wire clamp 24 is sewed in a hem 51 at the end of the bag by the seam 52. The wire clamp 24 is expanded by compressing its opposite ends 53—53 together to attach the bag on the bag ring 25 for insertion in the cleaner casing.

From the foregoing, it is apparent I have provided a filter bag which eliminates stitching in arcuate directions and as a result reduces the number of interruptions to adjust the material during the sewing of each of the seams.

While I have shown and described but one embodiment of my invention, it is to be understood that that embodiment is to be taken as illustrative only and not in a limiting sense. I do not wish to be limited to the particular structure shown and described but to include all equivalent variations except as limited by the scope of the claims.

I claim:

1. A dirt filtering bag adapted for use with a suction cleaner, comprising one piece of filter material forming the side wall and another piece

of filtering material forming the end wall of the bag, said end wall material secured at its periphery to the end periphery of said side wall material, said end wall material cut inwardly from its periphery and secured together to complete the end wall of the bag, and the meeting edges of said side wall material secured together to complete the side wall of the bag.

2. A dirt filtering bag adapted for use with a suction cleaner, comprising one piece of filter material forming the side wall and another piece of filtering material forming the end wall of the bag, said end wall material cut inwardly from its periphery, the original periphery of said end wall secured to the end of said side wall material, the meeting edges of said cut end wall and the meeting edges of said side wall material secured together to complete the bottom and side walls of the bag.

BELLE CORDRAY.
